TRIPLE VALVE BRACKET

Thomas Henry Birch, Wauwatosa, Wis.

Application April 2, 1941, Serial No. 386,447

2 Claims.

(Cl. 303—1)

My invention relates to a bracket especially intended for the L type of triple valve employed in the air brake system of railroad passenger cars, namely a bracket adapted to be applied to the pressure head of the brake cylinder at the point where the triple valve is generally applied, that is to say, the bracket is intended for the type of valve known as the pipeless valve, with all pipe connections being made to the pressure head of the brake cylinder.

The invention has for its object the provision of a bracket whereby the valve is applied in vertical position to the pressure head of the cylinder without need for changing any of the pipe connections and thus causes the valve to be vertically positioned and allowed to float, as it were, and consequently obviates the wear encountered at the lower side of the valve (which is of considerable weight) when arranged in horizontal position (the usual position of valve as at present employed) and which causes the valve to function improperly.

Another object of the invention is the provision of a bracket provided with ports adapted to register with the respective ports of the triple valve and the ports in the pressure head of the cylinder whereby air flow between the valve and the cylinder passes through the respective ports of the bracket which maintains the valve in upright position and consequently reduces the friction on the main piston and the slide valve and permits any wear on the bushing of the main piston in the triple valve to be uniform throughout the entire circumference of the bushing.

A further object of the invention is the provision of a ported bracket whereby the triple valve will be vertically positioned and the difficulty heretofore encountered of movement of the valve into undesired emergency position, due to excessive friction on the slide-valve, eliminated; the invention providing improved main piston and slide valve action due to the fact that the weight of the main piston and the slide valve combined is a factor in moving the main piston to release position, whereas in the present day arrangement the movement of the main piston and the slide valve is dependent entirely upon differentials of air pressures on opposite sides of the piston.

Furthermore, with the present arrangement dirt or foreign matter lodges between the slide valve and the slide valve seat and causes the valve and seat to become scored which results in leakage; whereas, with my arrangement this condition is eliminated because the dirt can readily free itself, and consequently great economy in maintenance and operation results.

The objects and advantages, as well as other advantages inherent in the invention, will all be

readily comprehended from the detailed description of the accompanying drawings wherein:

Figure 1 illustrates my improved bracket and triple valve in side elevation and applied to the pressure head of the cylinder of which only a portion is shown.

Figure 2 is a rear view of my improved bracket with portions broken away and shown in section.

Figure 3 is a vertical sectional view of the bracket, taken on the line 3—3 of Figure 2, viewed in the direction of the arrows.

Figure 4 is a detail sectional view of the bracket taken on the line 4—4 of Figure 3, looking in the direction of the arrows.

Figure 5 is a cross sectional view taken on the line 5—5 of Figure 3 looking downward.

The exemplification of the invention comprises a single piece casting 15 of angular shape having an upright or vertical portion 16 and a base or lower portion 17, the upper face whereof is disposed at right angles to the rear face of the vertical portion 16.

The upper end of the vertical wall 16 is shown with an annular flat faced boss portion 16a which matches the usual bolting face on the ported train line and air line receiving extension 18 on the head 19 of the brake cylinder 20.

The rear face of the boss portion 16a of the bracket is provided with suitable bolt-holes 21 which receive the bolts whereby the bracket is secured in place; and this rear face of the portion 16a is also provided with a central opening 22 and with suitably positioned openings or ports 23, 24, 25, 25 and 26; while opening 22 communicates with a port 27 which is located between port 26 and the forward wall of the upright portion 16 of the bracket. These ports all extend downwardly in the upright portion 16 and laterally into the base portion 17 of the bracket and all terminate in the upper face of the base portion which is also provided with a central opening 28 which corresponds to the opening 22 and is connected therewith by the port 27.

The bracket is preferably provided at opposite sides with reenforcing webs 29, 29.

The ported rear bolting face 16a of the bracket is identical with the present bolting face on the brake cylinders at present employed on railroad passenger cars; while the upper ported face of

the base portion 17 of the bracket corresponds with the bolting face on the present day type of triple valve; the ported upper face of base portion 17 being intended to receive the ported bolting face of the triple valve shown generally at 30 in Figure 1. That is to say, the ports in my improved bracket in reality constitute extensions or continuations of the ports formed in the brake cylinder as at present employed. With the ported bolting face of the triple valve disposed downwardly and secured on the ported horizontal face

of the base of the bracket, instead of against the vertical face of the cylinder head, as is the present practice, it is apparent that the triple valve will be positioned vertically instead of horizontally.

The various ports of the bracket correspond to the respective ports in the pressure head of the brake cylinder and in the attaching face of the triple valve and therefore perform the same functions; that is to say, port 23 in the bracket constitutes an extension of the exhaust ports in the cylinder head and in the attaching face of the triple valve—port 24 corresponds to the supplemental reservoir port of the triple valve and brake cylinder—ports 25, 25 correspond to the brake pipe ports, of which one or the other is used depending upon the side of the car from which the pipe connection is made, at which time the other port automatically blanks itself—port 26 corresponds to what is known as the brake cylinder port through which air passes to the brake cylinder and air returns for release—and port 27 (which terminates in the enlarged opening 22) corresponds to similar ports in the cylinder head and in the triple valve and known as the auxiliary reservoir port. The orifices of the various ports in the bracket are positioned in keeping with the corresponding ports in the attaching faces of the cylinder and of the triple valve and hence the ports through the bracket in reality constitute extensions of the respective ports of the cylinder and the triple valve.

The horizontally disposed base portion of the bracket on its upper face is shown provided with stud-bolts 31, positioned to register with the usual bolt receiving holes in the attaching flange of the triple valve shown at 30 in Figure 1.

As the respective air flow connections are in no way altered by my improved bracket, detail showing of the ports in the cylinder pressure head and in the triple valve is not deemed necessary as their construction and purposes are well known.

In present day practice, with the triple valve connected directly to the pressure head of the cylinder, the triple valve extends horizontally from the cylinder and hence the piston with its associated elements are disposed in a horizontal direction, and consequently the weight of the piston causes a hollow spot to be worn in the piston bushing at the lower side of the piston, which in turn causes main piston ring leakage and prevents a proper release of the brake, depending upon the amount of wear that has taken place, allowing the brake shoes to drag and to set up a dangerous condition. Furthermore, with the present day arrangement dirt or foreign matter becomes lodged between the slide valve and the slide valve-seat, causing a scoring of the valve and the seat which results in air leakage and hence necessitates frequent renovation or replacement.

With my improved bracket, the triple valve and its contained piston will be vertically disposed and wear on the bushing of the main piston will be uniform throughout the entire circumference of the bushing and production of the aforementioned leak spots will be prevented and a proper release of the brakes will obtain and the danger of dragging shoes will be eliminated. Then too, the lodgement of dirt or foreign matter between the slide valve and seat, due to the vertical disposition of the triple valve, will be impossible and hence the scoring of the valve and its seat will not occur.

In the present day arrangement of the triple valve with its main piston disposed horizontally, movement of the main piston and slide valve is entirely dependent upon differentials of air pressures on opposite sides of the piston; whereas in my proposed arrangement with the triple valve with its contained main piston disposed vertically, the weight of the main piston and slide valve combined constitute a factor in moving the main piston to release position; and then too, the excessive friction between the slide valve and its seat encountered in the present day arrangement is obviated and movement of the valve into undesired emergency position (at times occurring as a result of excessive friction) is prevented.

My improved bracket, with the triple valve disposed in vertical position, in actual practice has resulted in a more perfect functioning of the triple valve than has heretofore been the case; while at the same time application of my bracket to present equipment may be made without changes in the air brake piping and the use of my bracket will result in great economy in maintenance and operation.

The construction of bracket shown in the drawings is believed to be the best embodiment of the invention, but modifications may be possible without, however, departing from the spirit of my invention as defined by the appended claims.

What I claim is:

1. A bracket for supporting and pneumatically connecting the triple valve to the brake cylinder of the air brake system of a railroad car comprising a single piece angular casting having a vertical portion and a horizontally disposed base portion integral with the lower end of the vertical portion, the upper end of the vertical portion having a ported rear face matching the ported attaching face of the brake cylinder extension and adapted to be secured thereto, while the horizontally disposed base portion has a ported upper face matching the ported attaching face of the triple valve of an air brake system and to support the latter thereon in vertical position, said casting being provided with continuous passages between the respective ports in the vertically and the horizontally disposed faces.

2. A bracket for supporting the triple valve of a railroad car air brake system comprising, in combination with the ported head of a horizontally disposed brake cylinder and the ported face at one end of a triple valve, a casting having a vertical portion with a vertically disposed ported attaching face at the upper end on its rear side and a horizontal portion disposed laterally from the lower end of the vertical portion and terminating at its outer end in a horizontal upwardly disposed ported attaching face, said casting having a plurality of continuous passages between the respective ports in the two attaching faces, the ports in the first mentioned face matching the ports in the vertically disposed cylinder head and the ports in the second mentioned face matching the ports in one end of the triple valve; the horizontally disposed face being provided with upstanding stud bolts arranged to match the bolt-holes in the ported face of the triple valve whereby the latter is held in upright position; and means for securing the bracket to the cylinder head.

THOMAS HENRY BIRCH.
